UNITED STATES PATENT OFFICE.

WILLIAM E. WOODARD, OF LIMA, OHIO.

LATERAL-MOTION DRIVING-BOX.

1,250,747.

Specification of Letters Patent. Patented Dec. 18, 1917.

Application filed July 30, 1917. Serial No. 183,428.

To all whom it may concern:

Be it known that I, WILLIAM E. WOODARD, of Lima, in the county of Allen and State of Ohio, have invented certain new and useful Improvements in Lateral-Motion Driving-Boxes, of which the following is a specification.

This invention relates to lateral motion driving boxes for locomotives and the like and particularly to the general type of apparatus shown and described in Patent #1,181,194 issued May 2, 1916 to S. S. Riegel and the applicant. The present invention consists in an improvement of the device shown in said Letters Patent whereby the construction is simplified and the number of parts, as well as the weight of the parts, is greatly reduced, and whereby driving box bearings and cellars of normal length may be employed. In other and more general respects, the present invention has the same objects and advantages, and is designed for the same purposes, as the construction shown and described in said patent, to which attention is directed for detailed and specific statement thereof.

I have shown the preferred embodiment of my invention in the accompanying drawings, wherein—

Figure 1 is a diagrammatic side elevation of a locomotive embodying my improvements; Fig. 2 is an enlarged transverse section, taken on the center line of one of the driving axles, partly in elevation to illustrate certain of the parts; and Fig. 3 is an enlarged end elevation and partial section of the improved driving box.

The invention is shown applied in connection with a locomotive engine, the frame of which is of the standard "bar" type and comprises two side members which are spaced apart at the maximum distance available under the necessary limitations imposed by the width between driving wheel hubs. The portions of the side frame members in which the driving axles are fitted, comprise the usual top rail 1, bottom rail 2, and connecting vertical pedestal jaws 3 in which the end portions of the driving box structure are fitted between wedges 4^a and shoes 4^b. The spaces between the sections of the lower frame rail at the bottom of the pedestal are spanned by the usual pedestal ties 5, connected in any preferred manner.

In the Woodard and Riegel patent referred to, the pairs of driving boxes, which

are capable of vertical and lateral movement in the frame members, are spaced apart by a filler casting, through which the weight of the locomotive is transmitted to the driving boxes through the springs, the spring supporting beams and rocker members. The filler castings in such construction therefore serve as a spacing means for the driving boxes and also as the means whereby the driving boxes will be properly centered through the weight of the locomotive acting on the rocker members. I propose to eliminate the need of such filler castings by providing what may be termed a unitary driving box structure in the ends of which the driving box bearings and cellars are mounted.

This driving box structure, which I have indicated as a whole at A, is shown in Fig. 2 and comprises two open bottom sections 4, the inner ends of which are flanged as at 6, such flanges being bolted or secured together in any suitable manner. The openings in the sections 4 are of greater width than the major diameter of the driving axles and have their outer end portions arranged so as to receive the driving brasses 7 fitting the journals 8 of the driving axles. The overall length of the sections 4 is slightly less than the distance between the inside faces of the driving wheel hubs 9, the faces of the sections, if desired, being provided with renewable lateral wear plates 10. At their outer ends the sections 4 are each provided with the usual flanges 11 and 12, and intermediate plane or flattened portions 13 against which the shoes and wedges fitting the pedestal jaws bear. The flanges 11 and 12, however, instead of closely fitting the shoes and wedges as is customary, are spaced apart a distance greater than the width of the shoes and flanges so as to provide any desired amount of lost motion X for lateral play. It will of course be understood that the driving box structure has the usual freedom for vertical play in the pedestal jaws.

It will be seen from the foregoing that the structure is such that the necessity for separate independent means for laterally spacing the driving boxes is eliminated. The means for centering the driving box structure will now be described. That portion of the weight of the locomotive which is carried on the driving axles is transmitted to the driving box structure through the springs 14, which bear centrally on the seats

15 at the ends of the spring supporting beams 16, such beams extending transversely of the locomotive above the driving box structures and capable of vertical but 5 not lateral movement relative to the side frames. The springs are connected in the usual manner to the side frame members. The supporting beams are guided in vertical movement by the vertical guide faces 17 projecting downwardly below the spring seats, such guide faces fitting with a working 10 clearance between the rubbing plates 18 carried on top of the rail 1. The spring supporting beams 16 are supported on the driving box structures through the medium of 15 the rocker members 19, such rocker members having journals 20 at their lower ends fitting in open-topped bearings 21 formed on the driving box structure. At their tops 20 the rocker members have oppositely inclined or curved surfaces 22, upon which the supporting beam bears through correspondingly inclined or curved bearing faces 23, as will be clear from inspection of Fig. 2.

25 The operation of the device is as follows. When the driving box structure is laterally deflected in either direction from its normal position relative to the side frame members, by a lateral movement of the driving 30 wheels such as would take place when the locomotive passes from a straight to a curved portion of the track, its lateral movement swings each of the supporting rockers 19 upon one or the other of the pairs of 35 journals 20 in a direction opposite to that of the movement of the driving box structure. This movement of the rockers has a tendency to raise the supporting beams 16, such movement, however, being resisted by the 40 weight carried by the supporting beams. As the resistance is overcome, the supporting beams move upwardly as do the springs 14, without disturbance of their lateral relation to the side frame members or equalizer connections. When the locomotive passes from 45 a curved to a straight portion of the track, the weight on the rockers returns them and the driving boxes to normal central position.

50 The arrangement provides ample lateral motion and materially reduces the lateral thrusts or blows from the locomotive driving wheels, and since the driving box structures are maintained in central position, at 55 no time can the driving wheels deliver violent blows, as would be the case were the driving box structure permitted to shift and remain at either extreme of its lateral movement. The lateral blows are reduced by virtue of the fact that the rocker arrangement 60 sets up a yielding resistance to lateral motion, as will be readily understood.

The construction itself is simple and economical in manufacture, dispenses with a 65 large number of parts, and materially cuts

down weight as compared with the construction shown in Patent #1,181,194. The driving box structure is reinforced by the webs 24 which also serve to brace the bearings 21. Another important advantage of 70 my invention is that I am enabled to use driving box bearings and cellars of normal length. In the construction of the patent above referred to, the length of the bearings and cellars is materially increased. In order 75 to prevent end motion of the beam 16 with reference to the rockers, it will be observed that each of the rockers has a central projection or nose *a* which fits into a corresponding recess in the beam. 80

I claim:

1. In a locomotive engine, a combination of two side frame members, a rigid locomotive driving box structure inclusive of the driving boxes capable of relative vertical and lateral movement in said frame members, and means to control the lateral displacement of said box structure with reference to said frame members. 85

2. In a locomotive engine, a combination 90 of two side frame members, a rigid locomotive driving box structure inclusive of the driving boxes capable of relative vertical and lateral movement in said frame members, means limiting the lateral displacement of the box structure, and means to control the lateral displacement of said box structure with reference to said frame members. 95

3. In a locomotive engine, a combination 100 of two side members, a rigid locomotive driving box structure inclusive of the driving boxes capable of relative vertical and lateral movement in said frame members, and means under the influence of the supported weight of the locomotive to control the lateral displacement of said box structure with reference to said frame members. 105

4. In a locomotive engine, a combination 110 of two side frame members, a rigid locomotive driving box structure inclusive of the driving boxes capable of relative vertical and lateral movement in said frame members, and yielding means to control the lateral displacement of said box structure 115 with reference to said frame members.

5. In a locomotive engine, a combination of two side frame members, a driving axle having driving wheels, a rigid driving box structure inclusive of the driving boxes capable of relative vertical and lateral movement in said frame members, a driving box bearing at each end of said structure and embraced thereby, the said axle being journaled in said bearings, and means to control 120 the lateral displacement of the structure with respect to the frame members. 125

6. In a locomotive engine, a combination 130 of two side frame members, a driving axle having driving wheels, a rigid driving box

structure, capable of relative vertical and lateral movement in said frame members, and extending between driving wheel hubs, a pair of spaced flanges at the ends of said structure limiting the lateral displacement thereof with respect to the frame members, a driving box bearing at each end of said structure and embraced thereby, the said axle being journaled in said bearings, and means to control the lateral displacement of the structure with respect to the frame members.

7. In a locomotive engine, a combination of two side frame members, a driving axle having driving wheels, a rigid driving box structure capable of relative vertical and lateral movement in said frame members,

and extending between driving wheel hubs, said structure comprising a pair of driving boxes having their inner ends extended, 20 means for rigidly fastening said ends together, a pair of spaced flanges at the ends of said structure limiting the lateral displacement thereof with respect to the frame members, a driving box bearing at each end 25 of said structure and embraced thereby, the said axle being journaled in said bearings, and means to control the lateral displacement of the structure with respect to the frame members.

In testimony whereof, I have hereunto signed my name.

WILLIAM E. WOODARD.
